The ATTORNEY.

UNITED STATES PATENT OFFICE

RONALD A. McCANN, OF SWISSVALE, PENNSYLVANIA, ASSIGNOR TO THE UNION SWITCH & SIGNAL COMPANY, OF SWISSVALE, PENNSYLVANIA, A CORPORATION OF PENNSYLVANIA

RAILWAY SIGNALING

Application filed September 25, 1931, Serial No. 565,095. Renewed August 24, 1932.

My invention relates to railway signaling, and particularly to signaling for traffic movements from different directions over the same stretch of track.

5 One feature of my invention is the provision of means for inter-controlling the caution and proceed indications of opposing signals by apparatus requiring only three line wires.

10 I will describe one form of apparatus embodying my invention, and will then point out the novel features thereof in claims.

The accompanying drawing is a diagrammatic view showing one form of apparatus embodying my invention.

Referring to the drawing, the reference characters 1 and 1^a designate the rails of a stretch Y of railway track over which traffic may move in either direction. The rails 1 and 1^a are divided by means of insulated joints 2 into sections A—B, B—C, etc. Each of these track sections is provided with a track circuit including a battery 3 connected across the rails adjacent one end of the section, and a relay designated by the reference character R with a distinguishing exponent and connected across the rails adjacent the opposite end of the section.

20 A track repeater relay T^{P1} is controlled by track relays R², R³, R⁴ and R⁵. A second track repeater relay T^{P4} is controlled by track relays R¹, R², R³ and R⁴.

25 Signals, designated by the reference character S with distinguishing exponents, govern traffic movements over the stretch Y. Signals S¹ and S³ govern eastbound traffic movements over stretch Y, that is, traffic movements toward the right, as shown in the drawing. Signals S² and S⁴ similarly govern westbound traffic movements over stretch Y. As shown in the drawing, each of these signals is of the semaphore type.

30 Each of the signals S¹ and S⁴ operates a contact 12 which is closed when and only when the arm of the corresponding signal is in the stop position. Each of the signals S² and S³ operates a contact 16 which is closed when the arm of the corresponding signal is in the caution or proceed positions.

35 Contacts 12 of signals S¹ and S⁴ control sig-

nal repeater relays M¹ and M⁴, respectively.

Signal control relays H^{C1} and H^{C4} are controlled in any suitable manner by either coded or non-coded current from a remote point such, for example, as a train despatcher's office.

40 Signals S¹ and S⁴ are controlled by home relays H¹ and H⁴, respectively, and by distant relays N¹ and N⁴, respectively. Relays H¹ and N¹ are selectively controlled over a line wire a and a common wire o by relays H^{C1} and M¹. Relay H¹ is also controlled by repeater relay T^{P1}. Relay N⁴ is also controlled by relays H⁴ and H^{C4}. Relays H⁴ and N⁴ are selectively controlled, similarly to relays H¹ and N¹, over a second line control wire b and common wire o.

45 Signals S² and S³ may be controlled in any suitable manner. The controls for these signals form no part of my present invention, and are therefore not shown in the drawing.

50 As shown in the drawing, all parts are in their normal condition, that is, the track sections are unoccupied, each relay H and each relay N is deenergized, and each signal S is indicating "stop". Since the track sections are unoccupied, each relay R is energized, and relays T^{P1} and T^{P4} are therefore also energized. The circuit for relay T^{P1} passes from terminal x¹ of a source of current not shown in the drawing, through contact 4 of relay R⁵, contact 5 of relay R⁴, contact 6 of relay R³, contact 7 of relay R², and the winding of relay T^{P1} to common wire o which is connected to the other terminal of the same source of current. The circuit for relay T^{P4} passes from terminal x² of a second source of current not shown in the drawing, through contact 8 of relay R¹, contact 9 of relay R², contact 10 of relay R³, contact 11 of relay R⁴, and the winding of relay T^{P4} to common wire o which is also connected to the other terminal of the second source of current.

55 With the arm of signal S¹ in the stop position, relay M¹ is energized by a circuit passing from terminal x¹, through contact 12 of signal S¹, and the winding of relay M¹ to wire o. With the arm of signal S⁴ in the stop position, relay M⁴ is energized by a similar circuit which includes contact 12 of signal S⁴.

I will now assume that the despatcher desires to permit an eastbound train to proceed over stretch Y. He will therefore cause relay H^{C1} to become energized. Relay H^{C1} , upon becoming energized, closes its front contact 14—14^a, thereby completing a circuit for energizing relay H^1 passing from terminal x^1 , through contact 13^a—13 of relay M^4 , wire a , contact 14—14^a of relay H^{C1} , contact 15 of relay T^{P1} , and winding of relay H^1 to wire o . Relay H^1 , upon becoming energized, completes, through its contact 19, an operating circuit for signal S^1 , which causes the arm of signal S^1 to move to its caution position.

When the arm of signal S^1 leaves the stop position, contact 12 of signal S^1 opens, causing relay M^1 to become deenergized. Relay M^1 , upon becoming deenergized, completes a circuit for relay N^1 if signal S^3 is indicating either caution or proceed. This circuit for relay N^1 passes from terminal x^1 through contact 16 of signal S^3 , contact 14^b—14 of relay H^{C4} , wire b , contact 13—13^b of relay M^1 , contact 17 of relay H^{C1} , contact 18 of relay H^1 , and the winding of relay N^1 to wire o . Relay N^1 , upon becoming energized, completes through its contact 20 an operating circuit for causing the arm of signal S^1 to move from the caution to the proceed position.

When a train passes signal S^1 , deenergizing relay R^2 , the circuit for relay T^{P1} becomes opened at contact 7 of relay R^2 , and hence relay T^{P1} becomes deenergized. Relay T^{P1} being deenergized, contact 15 of this relay opens the circuit for relay H^1 . Relay H^1 being deenergized, contact 19 of this relay opens the circuit for operating the arm of signal S^1 to the caution position, and contact 18 of this relay opens the circuit for relay N^1 . Contact 20 of relay N^1 thereupon opens the circuit for operating the arm of signal S^1 to the proceed position. The arm of signal S^1 therefore now returns to the stop position. Relay T^{P1} will remain deenergized until the train has passed through all the sections from B to F, and hence signal S^1 will continue to indicate stop during this time.

The operation of the apparatus for westbound traffic movements is similar to that just described for eastbound traffic movements. It will be noted that relay H^{C1} upon becoming energized opens its back contact 14—14^b in the circuit for relay N^4 . It will also be noted that relay M^1 , upon becoming deenergized, opens its front contact 13—13^b in the circuit for relay H^4 . It will be clear, therefore, that relay H^4 cannot become energized as long as relay M^1 is deenergized, and that relay N^4 cannot become energized as long as relay H^{C1} is energized. The arm of signal S^4 can therefore not be operated to either the caution or the proceed position as long as signal S^1 is indicating either caution or proceed.

Similarly, if the arm of signal S^4 has been operated to the caution or proceed position, signal S^1 cannot be operated to the caution or proceed position until the arm of signal S^4 has been returned to the stop position.

From the foregoing description and the accompanying drawing, it is clear that, with apparatus embodying my invention, the inter-control of two opposing signals, such as signals S^1 and S^4 , is effected with the use of only two line control wires a and b and a common wire o .

Although I have herein shown and described only one form of apparatus embodying my invention, it is understood that various changes and modifications may be made therein within the scope of the appended claims without departing from the spirit and scope of my invention.

Having thus described my invention, what I claim is:

1. In combination, a first and a second signal governing traffic movements in opposite directions over a given stretch of railway track, a signal repeater relay, a second signal repeater relay, means controlled by said first signal for energizing said first relay only when said first signal indicates "stop", means controlled by said second signal for energizing said second relay only when said second signal indicates "stop", a control relay for said first signal, a second control relay for said second signal, a circuit including a front contact of said first control relay and a front contact of said second repeater relay for causing said first signal to display a "caution" indication, a second circuit including a front contact of said second control relay and a front contact of said first repeater relay for causing said second signal to display a "caution" indication, a third circuit including a back contact of said second control relay and a back contact of said first repeater relay for causing said first signal to display a "proceed" indication, and a fourth circuit including a back contact of said first control relay and a back contact of said second repeater relay for causing said second signal to display a "proceed" indication.

2. In combination, a first and a second signal governing traffic movements from a first and a second direction, respectively over a given stretch of railway track, a first and a second control wire and a common wire, means including said first control wire and said common wire for controlling the caution indication of said first signal and the proceed indication of said second signal, and means including said second control wire and said common wire for controlling the caution indication of said second signal and the proceed indication of said first signal.

3. In combination, a first and a second signal governing traffic movements from a first and a second direction respectively over a

given stretch of railway track, a control wire, a second control wire, a circuit including said first control wire for causing said first signal to display a caution indication, a second 5 circuit including said second control wire for causing said second signal to display a caution indication, a third circuit including said second control wire for causing said first signal to display a proceed indication, and a 10 fourth circuit including said first control wire for causing said second signal to display a proceed indication.

4. In combination, a first and a second signal governing traffic movements from a first 15 and a second direction respectively over a given stretch of railway track, a signal repeater relay energized when said first signal indicates "stop", a second signal repeater relay energized when said second signal indicates "stop", means controlled by a front 20 contact of said first relay for controlling a caution indication of said second signal, means controlled by a back contact of said first relay for controlling a proceed indication of said first signal, means controlled by a front contact of said second relay for controlling a caution indication of said first signal, and means controlled by a back contact 25 of said second relay for controlling a proceed indication of said second signal.

5. In combination, a first and a second signal governing traffic movements from a first and a second direction respectively over a given stretch of railway track, a control relay for said first signal, a second control relay for said second signal, a circuit including a front contact of said first relay for controlling a caution indication of said first signal, a second circuit including a front contact of said second relay for controlling a caution indication of said second signal, a third circuit including a back contact of said first relay for controlling a proceed indication of said second signal, and a fourth circuit including a back contact of said second relay for controlling a proceed indication of said first signal.

In testimony whereof I affix my signature.

50
